(57) CLAIM

The ornamental design for a bag, as shown and described.

DESCRIPTION

1. Bag

1.1 : Perspective

1.2 : Front

1.3 : Back

1.4 : Right

1.5 : Left

1.6 : Top

1.7 : Bottom

1.8 : Perspective

1.9 : Top

The bag comprises a body and a shoulder strap; the body, seen from the front or from behind, presents a roughly trapezoidal shape flaring upwards, with the lower corners rounded and the upper side presenting a sinuous profile, its central part being raised; the upper central part of the front wall of the body has a triangular opening with rounded corners, flaring upwards; a hook extends from the inside of the rear wall of the body and through said opening in the front wall; a strap extends across the central portion of the upper edges of the body of the bag, one end of the strap sewn to the rear wall of the body, its other end forming a loop which can be connected with said hook.

1 Claim, 9 Drawing Sheets
